UNITED STATES PATENT OFFICE.

GEORGE COLBOURNE, OF PITTSBURGH, PENNSYLVANIA.

AUTOMOBILE PROTECTION DEVICE.

Application filed May 17, 1921. Serial No. 470,321.

To all whom it may concern:

Be it known that I, GEORGE COLBOURNE, a citizen of the United States, and a resident of Pittsburgh, in the county of Allegheny and State of Pennsylvania, have invented a new and useful Improvement in Automobile Protective Devices, of which the following is a specification.

My invention relates to automobile protective devices, and it has particular relation to devices for controlling the supply of fuel for gas engines.

One object of my invention is to provide a protective device of such character as to effectually prevent unauthorized use of an automobile.

The second object of my invention is to provide an arrangement in which the parts of the mechanism for rendering a gas engine operative and inoperative are removable and interchangeable whereby the engine can not be operated in the absence of one of the parts.

Numerous devices have been proposed heretofore for the purpose of preventing the unauthorized use or theft of automobiles. Such devices generally comprise a member which has two positions in one of which the engine is rendered inoperative. Protective devices may, however, be adjusted to their operative positions in case the lock is broken. The parts necessary for the operation of the engine are not removed therefrom.

According to the present invention, I provide two independent, removable and interchangeable parts for controlling the manifold of a gas engine. One of these parts or the vent shutter is provided with an opening corresponding in size to that of the engine manifold. The other or blind shutter has no opening and when it is substituted for the first shutter, it effectually prevents the operation of the engine by obstructing the engine manifold.

In the accompanying drawing, Fig. 1 is a side view in elevation, of the carburetor and manifold of an automobile engine with my invention applied thereto.

Figs. 2 and 3 are respective side and end views of the shutter-case.

Fig. 4 is a view, partially in section and partially in elevation, of the shutter-case and the vent shutters, the latter being partially withdrawn.

Figs. 5 and 6 are respectively side and edge views of the vent shutter.

Fig. 7 is a side view of the solid or blind shutter.

Referring to the drawing, a manifold 1 of a usual gas engine is connected to a carburetor 2 of any suitable or usual type. The opening or passageway for connecting the carburetor to the manifold is controlled by a protective device 2 comprising a shutter-case 3^a which is inserted between the adjacent ends of the manifold and the carburetor outlet. Each of these associated parts is provided with laterally extending flanges 4 having suitable openings for the reception of bolts 5. The bolts are provided with nuts 6, lock washers 7 and with pins 8, of hardened steel, for securely and permanently retaining the nuts 6 in operative position. The pins 8 prevent the removal of the nuts 6 in the absence of special tools for such purpose.

The shutter-case 3^a, as shown in detail in Figs. 2, 3 and 4, is provided with an opening 8^a which corresponds in size to that of the carburetor outlet and the manifold. The device 3 is provided with a laterally extending slot 9 of wedge shape for the reception of the one or the other of two shutters which may be termed, respectively, the vent shutter 10 and the blind shutter 11. The vent shutter 10 is provided with an opening 12, the diameter of which corresponds to that of the opening 8^a and the openings in the associated parts. The blind shutter 11 has no opening, and when it is in position, the opening in the manifold is effectually closed. Each of the shutters is provided with a hole 13 by means of which a padlock or other suitable locking device may be inserted for the purpose of preventing its unauthorized removal.

The operation of my improved protective device will be readily understood from the foregoing description. When it is desired to operate the car, the vent shutter 10 is inserted, as illustrated in Fig. 1, and is locked in position by a padlock 14 to prevent the unauthorized tampering with, and the consequent disabling of, the machine. When the parts are assembled in the manner described, the engine operates in the usual or normal manner.

When it is desired to park the automobile or to permit it to stand in the absence of the driver, the vent shutter 10 is removed and replaced by the blind shutter 11, the latter being securely locked in position by the padlock 14. The vent shutter is not allowed to

remain in the machine, but is retained in the possession of the driver. It is now impossible for the machine to be operated by any person except the driver without breaking 5 the lock, removing the blind shutter 11, and closing the end portions of the slot 9. This procedure is difficult of execution because all the parts are constructed of highly tempered and hardened steel.

10 It is practically impossible, also, to so close the openings of the slot 9 as to render the mechanism operative. In addition, it will require considerable time and the use of considerable force to destroy the locking 15 device and to take such steps as are necessary to render the machine operative. The danger of detection is so great that it is entirely unlikely that an attempt will be made to either use the machine without the authority 20 of the owner or to attempt the theft of the same.

It will be noted that I provide an arrangement in which the necessary parts for the operation of the machine are entirely removed 25 from the latter when it is desired to prevent its unauthorized use.

A device constructed in accordance with my invention may be manufactured at low cost. It is of such nature that it may constitute 30 a standard part of any and all automobiles. It may also be incorporated in the structure of automobiles at any time during their operation. The above and other advantages will be apparent to those skilled in 35 the art to which my invention appertains.

I claim as my invention:

1. A protective device comprising a member for conducting fluids having a lateral opening and a pair of independent removable members that cooperate with said opening to respectively permit only or prevent only the passage of fluid through said conducting member, said removable members being non-rotatable relatively to said conducting member.

2. A protective device comprising a member for conducting fluids having a lateral opening and a pair of independent removable members that cooperate with said opening to respectively permit only or to prevent only the passage of fluid through said conducting member, said members being interchangeable.

3. A protective device comprising a member for conducting fluids having a lateral opening and a pair of independent interchangeable non-rotatable shutters that coop-

erate with said opening to respectively permit or prevent the passage of fluid through 60 said conducting member.

4. A protective device comprising a member for conducting fluids having a lateral opening and a pair of independent removable members that cooperate with said opening to respectively permit only or to prevent only the passage of fluid through said conducting member, one of said removable members being so arranged that it may be locked 65 in operative position.

5. A protective device comprising a member for conducting fluids having a lateral opening and a pair of independent interchangeable non-rotatable shutters that cooperate with said opening to respectively permit or prevent the passage of fluid through 75 said conducting member, one of said shutters being so arranged that it may be locked in operative position.

6. A protective device comprising an engine manifold having a pair of lateral openings extending therethrough, a pair of independent and interchangeable shutters removably associated with said openings for permitting or preventing the passage of fuel 80 through said manifold according as the one or the other shutter is in position in said openings, said shutters being non-rotatable with respect to said manifold.

7. A protective device comprising an engine manifold having a pair of lateral openings extending therethrough, a pair of independent, non-rotatable and interchangeable shutters of highly tenacious material removably associated with said openings for permitting or preventing the passage of fuel 90 through said manifold according as the one or the other shutter is in position in said openings.

8. A protective device comprising an engine manifold having a pair of lateral openings extending therethrough, a pair of independent and interchangeable shutters removably associated with said openings for respectively permitting only or preventing only the passage of fuel through said manifold according as the one or the other shutter is in position in said openings, one of said shutters having an opening whereby a lock may be inserted.

In testimony whereof, I have hereunto 110 subscribed my name this 14 day of May, 1921.

GEORGE COLBOURNE,
